The ornamental design for a valve, as shown and described.

DESCRIPTION

FIG. 1 is a perspective view of the valve of our design, shown in an exemplary operational environment wherein the valve cap is seated on a valve stem in a first orientation; FIG. 2 is a perspective view of the valve of our design, shown in an exemplary operational environment wherein the valve cap is seated on a valve stem in a second orientation; FIG. 3 is a side elevation view of the valve of our design; FIG. 4 is a top view of the valve of our design; FIG. 5 is a side elevation view of the valve of our design, taken from the opposite side of that shown in FIG. 3; and, FIG. 6 is a bottom view of the valve of our design. The broken lines in FIGS. 1 and 2 depicting a valve stem are environmental subject matter and form no part of the claimed design. The dash-dot-dot-dash line depicts the boundaries of the claim in the bottom view. All other broken lines depict portions of the valve that no part of the claimed design.
